SOAP PASTE DISPENSING APPARATUS

Bryant H. Gardner, Granby, Mass., and Frederick W. Yardley, Simsbury, Conn., assignors to The Chemical Corporation, Springfield, Mass., a corporation of Massachusetts

Application September 9, 1948, Serial No. 48,446

2 Claims. (Cl. 222—39)

1

This invention relates to soap dispensing apparatus of the type used primarily for measuring out small quantities of hand pastes, such as protective pastes or soap, in washrooms, lavatories and similar places.

The invention has for its main object to provide a storage and dispensing container combining simplicity of construction, positive discharging action, indicating means for measuring the quantity of hand paste dispensed and rigidity of mounting.

Other objects and advantages will be apparent for an understanding of the drawings and their accompanying description.

In the drawings:

Fig. 1 is a side elevation of the apparatus of the invention broken away in part for better illustration;

Fig. 2 is a vertical section taken on line 2—2 of Fig. 1;

Fig. 3 is a horizontal section taken on line 3—3 of Fig. 1;

Fig. 4 is a fragmentary sectional view taken on line 4—4 of Fig. 3;

Figs. 5 and 6 are detail views of cooperating locking means for the dispenser cover;

Fig. 7 is a fragmentary detail of the means for indicating the angular movement of the dispenser shaft;

Fig. 8 is a view showing a modified form of discharge slot; and

Fig. 9 is a view showing a modified means for indicating angular movement of the dispenser shaft.

In Figs. 1 and 2 paste dispensing apparatus embodying the features of my invention and generally indicated by the numeral 1 is shown removably mounted on a wall or beam 2 by means of blocks 3 and 4 cut to form a dovetail joint as shown. Block 4 and the dovetail groove of block 3 are tapered to ensure firm interlocking of the cooperating joint parts. In addition, a set screw 5 (Fig. 3) serves to prevent easy withdrawal of the dispenser from its mount.

The dispenser 1 includes a storage compartment or reservoir 6 consisting of a cylindrical wall member 7 and a bottom plate 8 fixed thereto. The bottom plate 8 is provided with a radial slot 9 partially covered by an upturned overlying shearing edge 10 of a deflector plate 11, which plate is fixed to the bottom plate 8 by rivets as shown in Figs. 1, 3 and 4. In addition the bottom plate 8 contains a bearing socket 12 to receive the lower end of a shaft 13 which is carried by and extends downwardly from a cover

2

member 14. The cover 14 is provided with a hub portion 15 suitably proportioned to properly journal said shaft 13. A shoulder 16 is provided on the shaft 13 to prevent accidental withdrawal of said shaft through its bearing. A handle 17 is secured to shaft 13, as by a locking pin 18 (Figs. 1 and 2). At its lower end the shaft 13 is slotted to receive a paddle 19, which paddle is fixed within said slot in shaft 13 by rivets 20.

10 To secure and maintain a tight fit between cover and container the cover 14 is provided with a downwardly projecting portion 21 which fits the inner bore of the walls 7 and which contains locking means as shown in Figs. 5 and 6. In Fig. 5 a spring pressed lock pin 22 extends through a bore 23 in the wall 7 when the cover and container are in locked position; and diametrically opposite and near the upper edge of wall 7 a pin 24 fixed in said wall and protruding inwardly operates with a locking groove 25 formed in portion 21 of cover 14 as shown in Fig. 6.

In Figs. 1, 2 and 7 means for providing an indication of the angular movement given shaft 13 are shown comprising a coarse vertical fluting or grooving 26 formed in the outer surface of hub 15 and a spring pressed ball 27 held in a bore 28 formed in one of two enlargements 29 depending from handle 17, spring 30 being compressed between the ball and a threaded plug 31. Ball 27 imparts only a slight restraining action on the shaft 13. However, if shaft 13 is rotated, the intermittent displacement and return of the spring pressed ball results in an audible signal as the ball moves in and out of the grooves 26 in turn. In addition to the audible signal just described, the impact of the spring pressed ball 27 even though slight, results in a slight jarring action which is imparted to handle 17, which jar may be felt by anyone grasping and turning said handle. An audible and touch sensitive signal is thus provided which is indicative of the amount of paste dispensed without the necessity of visual inspection. Since the dispensers will usually be mounted approximately at waist height for convenience of operation, visual inspection is inconvenient and an audible or touch sensitive signal is of substantial advantage to the efficient and economical operation of the dispenser.

A modified arrangement for indicating the extent to which the shaft 13 is turned is shown in Fig. 9. As there shown the hub 15 is recessed at 37 to receive a coarse ratchet 36 fixed in the shaft 13 and engaged by a spring pawl 38 secured to the wall of the recess 37. The movement of the pawl 38 over the coarse ratchet teeth gives an

audible and tactile indication of the rotation of shaft 13 similar to that previously described.

Fig. 8 shows a modified form of discharge slot in which the deflector plate is eliminated, and a shearing edge 39 is formed from a slightly upturned portion 40 of bottom plate 41. In this modification the material of bottom plate 41 may be thin enough to permit slot 42 to be formed by punching the material of said plate rather than by cutting or slitting. In this way the formation of slot and shearing edge may be accomplished in one operation.

In use, the dispenser 1 is filled or partially filled, with hand paste. Pastes of this type are fluid enough to level off in the bottom of the container, but are viscous enough so that they will not flow by their own weight through the restricted opening of the discharge slot 9. Thus we have the container filled with paste in which is suspended the paddle shaft 13 and paddle 19. Rotation of the paddle shaft and paddle by means of the handle 17 results in the rotary displacement of the body of paste which surrounds said paddle. The paste nearest bottom plate 8 is deflected by shearing edge 10 of the deflector plate 11 into slot 9 through which it is discharged in a thin wafer-like ribbon. The discharge action will continue as long as the paddle is rotated.

The action is the same for the modified form of discharge slot shown in Fig. 8. In this case however the shearing edge 39 of the upturned portion 40 deflects the paste into the discharge slot.

What we claim is:

1. A hand paste dispenser comprising a cylindrical reservoir for the paste having a bottom provided with a constantly open narrow discharge opening, means along one edge of said opening to guide the paste through the opening, a removable cover member provided with means for locking the cover to the reservoir, said cover having a centrally positioned outwardly extending hub, a shaft rotatably mounted in said hub and held against axial movement relative thereto, said shaft extending downwardly into the reservoir, a bearing socket fixed to the bottom of the reservoir for receiving the lower end of said shaft, a thin flat paddle fixed to the lower portion of said shaft and extending transversely thereof

5 in a vertical plane, the lower edge of the paddle being positioned closely adjacent the bottom of the reservoir, a handle fixed to the shaft outwardly of said hub, and means rotatable with the shaft and engageable with means carried by the hub to form an audible and touch sensitive signal means to indicate the amount of rotation imparted to the paddle shaft.

2. A hand paste dispenser comprising a cylindrical reservoir for the paste having a bottom provided with a constantly open narrow discharge opening, means along one edge of said opening to guide the paste through the opening, a removable cover member provided with means for locking the cover to the reservoir, said cover having a centrally positioned outwardly extending hub, a shaft rotatably mounted in said hub and held against axial movement relative thereto, said shaft extending downwardly into the reservoir, a bearing socket fixed to the bottom of the reservoir for receiving the lower end of said shaft, a thin flat paddle fixed to the lower portion of said shaft and extending transversely thereof in a vertical plane, the lower edge of the paddle being positioned closely adjacent the bottom of the reservoir, a handle fixed to the shaft outwardly of said hub, and having a depending portion opposing the outer surface of the hub, said surface being coarsely fluted, and a spring actuated ball member carried by said depending portion and engaging the flutes on the hub to provide an audible and touch sensible indication of the amount of rotation imparted to the shaft.

BRYANT H. GARDNER.
